UNITED STATES PATENT OFFICE.

WILLIAM CLARK, OF UNION, NEW JERSEY, ASSIGNOR TO ANDREW McLEAN CO., OF NEW YORK, N. Y., A CORPORATION OF NEW JERSEY.

HATBAND.

Application filed May 7, 1924. Serial No. 711,657.

To all whom it may concern:

Be it known that I, WILLIAM CLARK, a citizen of the United States, and a resident of the town of Union, in the county of 5 Hudson and State of New Jersey, have invented certain new and useful Improvements in Hatbands, of which the following is a specification.

The invention relates to improvements in 10 hat bands and more particularly to a flexible cushion band for ladies' hats.

Prior to the prevailing style of bobbed hair it was customary for a hat frame manufacturer to make the frames or shapes of 15 a standard headsize and this standard headsize would accommodate a vast majority of the purchasing public, this being due to the fact that if a woman had a large amount of hair she could readily arrange it to suit the 20 size of the hat. Today, due to the bobbed hair the manufacturer must make many sizes of frames, varying widely in range. This naturally necessitates carrying a very large stock and as the styles of both hats and 25 bobbed hair change constantly a large part of this stock is often wasted and unused. One of the objects of this invention is to provide a band of such flexibility as to obviate the necessity of making so many different sized frames. The flexible band is concealed by the lining of the hat and permits 30 of a great elasticity of the headsize without affecting the shape of the hat.

Another advantage of the improved band 35 is that, due to its elasticity and flexibility, it holds the hat securely on the head without any discomfort to the wearer. Due to the cushioning effect it readily conforms to the shape and size of the head and thus, not only 40 fits well, but with a greater degree of comfort than any other style hat.

The band is made of an elastic fabric cut 45 with the threads on a bias or at an angle of approximately 45° to each other. The piece 50 of fabric is folded over on itself and sewed to the hat frame. The band is preferably sewed in the hat by the frame manufacturer but it may just as readily be made as a separate article of manufacture and sold to the 55 purchaser who may easily attach it to any hat she might have.

With the foregoing and other objects in view, the invention consists in the novel features hereinafter fully described in the fol-

lowing specification and pointed out in the 55 claims.

In the drawings illustrating and forming a part thereof:

Fig. 1 is a sectional view of a hat frame with the improved hat band in position. In 60 this view the interior lining is also shown and part of it is broken away for clearness of illustration.

Fig. 2 is a plan view of a strip of the material of which the band is made before being folded.

Fig. 3 is an enlarged detail plan view of 70 a piece of the material showing how the threads run at an angle of approximately 45° to each other.

Fig. 4 is an elevation, partly in section of a form of band which may be made up and sold as a separate article of manufacture.

Fig. 5 is a detail sectional view taken on the line 5—5 of Fig. 4.

Fig. 6 is an elevation of another form 75 similar to Fig. 4. This form is readily adjustable so as to be attached to any sized hat; and

Fig. 7 is a view of the form shown in 80 Fig. 6, opened out.

The reference numeral 10 designates the body of the hat frame, having the brim 11 and the usual wire reinforcement 12. This frame or shape is of usual construction in 85 all respects and might be made of any stiffened material or wire.

The improved flexible cushion band 14 is secured to the hat by stitching 15 and is 90 covered and concealed by the usual inner lining 17 of the hat. As shown in Fig. 2 this band is formed of a strip of woven material having its threads cut on the bias or at an angle of approximately 45° to the edge of the material. This sheet of material 95

18 is folded over or doubled on itself and secured together at or near its edges by the stitching 15 which also secures the band to the hat. In this way an elastic, flexible roll 19, as illustrated in Fig. 1, is made and this forms a cushion which readily conforms to the shape and size of the head and adds a great degree of comfort to the wearer. The great elasticity of the rolled band also does away with a number of different sized 100 frames the manufacturer would otherwise have to make.

The fabric itself is illustrated particu-

larly in Fig. 3 where it may readily be seen that when the woven material is cut in a strip it is so cut that the threads run approximately at an angle of 45° to the edge 5 of the material. The material is preferably made of cotton yarn which is sized and starched and given what might be termed an elastic finish. Due to cutting the strips with the threads on a bias, before the strip 10 is folded, the elastic and flexible value of the strip is greatly increased over what it would be if the threads were running parallel with and at right angles to the edges of the strip.

15 Fig. 3 shows a form in which the band 14^a is made up so as to be sold apart from the hat and attached in any hat the purchaser desires. The band is made of the same material 18^a and formed of a strip such as is 20 shown in Figs. 2 and 3. To give it a better and more durable finish, when it is folded over to form the roll 19^a, its edges are taped as at 20 and secured together by the stitching 15^a. At its butt ends when the 25 band is brought together, it is preferably turned in as at 21 and secured together by stitching 22 as shown in Fig. 5.

Figs. 6 and 7 illustrate a form similar to Fig. 4, but instead of being brought together 30 and secured at its ends after being folded over, the band 14^b has its ends left open and taped as at 23. The tape 20^b and line of stitching 15^b secure the edges in the same way as shown in Fig. 4. In this form the 35 end 24 is tapered sufficiently so that this end may readily be introduced into the other end as shown in Fig. 6. In this way the band

may be contracted or expanded to any desired size and then secured in position in the hat.

While a preferred embodiment of the invention has been described it is desired to point out that changes could readily be made without departing from the spirit of the invention or the scope of the claims.

What I claim as new is:

1. A hat band formed of a woven fabric, sized or starched and given an elastic finish, cut so that the threads are at an angle of approximately 45° to the edge of the fabric, 50 doubled over on itself so as to be loop form in cross section, the opposed walls of the loop being held apart by the elasticity of the band and sewed at or near its edges.

2. A hat band formed of a woven fabric, 55 sized and starched and given an elastic finish, cut so that the threads are at an angle of approximately 45° to the edge of the fabric, doubled over on itself so as to be loop form in cross section, the opposed walls 60 of the loop being held apart by the elasticity of the band, taped and sewed at its edges and secured together at its ends.

3. A hat having in combination a frame and a band, said band being formed of a 65 woven fabric, sized and starched and given an elastic finish, cut so that the threads are at an angle of approximately 45° to the edge of the fabric, doubled over on itself so as to be loop form in cross section, the 70 opposed walls of the loop being held apart by the elasticity of the band, and sewed at or near its edges to the frame.

WILLIAM CLARK.
